METHOD AND COMPOSITION FOR DESTROY-
ING TREE STUMPS

Charles S. Walters and Kenneth R. Peterson, Urbana, Ill., assignors to The University of Illinois Foundation, Urbana, Ill., a corporation of Illinois

No Drawing. Filed May 15, 1958, Ser. No. 735,351

15 Claims. (Cl. 47—58)

This invention is concerned with the substantial destruction of tree stumps. It is more directly concerned with a method and composition for facilitating the conflagration of tree stumps.

In general, the removal of substantial numbers of tree stumps in land clearing operations or the like is best carried out employing mechanical, self-propelled equipment such as bulldozers, or using explosives. Such positive techniques which involve uprooting the stumps, however, are not readily adaptable or available, without unjustifiable expense or hazards, for use by homeowners, farmers, or others who have the occasional problem of stump removal.

Removal of small numbers of tree stumps, or stumps which cannot be removed by uprooting for various reasons is generally effected by burning the stump to destroy that portion above ground level. Thereafter the area is graded to eliminate evidence of the unsightly stump.

To facilitate the burning it has been the practice to disperse saltpeter (potassium nitrate) through the stump by drilling holes in the exposed trunk and root structures and disposing portions of the saltpeter in the several holes. By natural diffusion processes the saltpeter would disperse throughout the stump. Kindling of various sorts, such as scrap wood, corncobs and the like would be piled about the stump and ignited. Even though sufficient time would elapse to permit the substantially complete diffusion of the chemical in the stump before igniting the stump, unsatisfactory results would be produced.

The prevalence of the Dutch elm disease has further emphasized the problem of stump removal because arboriculturists currently recommend prompt cutting of dead trees and the destruction of the above-ground portions because they serve as a refuge for the bark beetle that transmits the Dutch elm disease to healthy trees. Cutting the trees leaves an unsightly stump; decayed stumps represent a physical hazard to the public as well as to the homeowner.

According to this invention there has been found a practical and economical composition and method for effecting the substantial removal of unsightly and hazardous stumps by burning. In carrying out this invention a water-soluble salt containing a copper ion or a water-soluble salt containing a chromium ion is employed as the glow-inducing chemical which is dispersed in the stump. Suitable copper salts include but are not limited to copper chloride, copper sulfate, copper acetate, copper chlorate, copper dichromate, copper nitrate, and others. Chromium ion containing salts include the alkali metal chromates and dichromates, e.g., sodium chromate, potassium dichromate; chromic acid, and others.

Although effective results are produced employing either the chromium or copper salts singly, efficiency of the burning is enhanced utilizing admixtures of copper and chromium salts. It has also been found that the

use of water-soluble salts of iron, lead, manganese, and/or molybdenum in the copper and/or chromium salt-containing, glow combustion-inducing composition can provide compositions which have superior properties for application in carrying out the objectives of this invention. Non-limiting examples of suitable compounds of iron, lead, manganese, and molybdenum are included in the following non-limiting tabulation:

Iron	Lead	Manganese	Molybdenum
bromide	acetate	chloride	alkali metal
chloride	chlorate	bromide	molybdates
acetate	nitrate	oxides	
citrate		sulfates	
nitrate			
oxalate			
sulfate			

In employing the process of this invention a plurality of holes in a sufficient number and deep enough to receive the selected amount of glow combustion-inducing composition are drilled in the exposed stem and root structure of the stump. It is preferred that the stem portion be removed as close to the ground level as possible.

A composition of this invention is introduced, preferably in dry form, in the several holes. The diffusion of the composition through the stump is permitted to take place. The time required for diffusion depends upon such factors as moisture content of the stump, type of wood, size of stump, amount of glow combustion-inducing composition employed, etc. To obtain satisfactory results it is preferred that the diffusion take place for about four months before igniting the stump. Shorter times, however, might be used. For example, satisfactory results have been reported for a two week diffusion period. During this period additional amounts of the composition can be placed in the stumpholes. After a sufficient time for diffusion elapsed the stump is ignited by piling kindling about the stump and firing it. When the stump is burning, generally no flame is visible; however, if satisfactory diffusion has taken place and the required amounts of composition employed a strong glowing combustion will persist until the stump is substantially destroyed. During the burning of the stump a suitable shield can be positioned above the burning stump not only to ward off any precipitation but also to form a reflector for reradiating the heat produced during the burning. The shield which also prevents any sparks or embers from flying about, can be made from any weather and fire resistant sheet material which will not substantially deform under the heat conditions experienced during the burning.

The amounts of glow combustion-inducing composition employed will depend upon a number of factors, primarily the size of the stump and the nature of the wood structure which permits the diffusion of the composition throughout the stump. In general, an amount sufficient to produce an equilibrium concentration in the stump depending upon its moisture content is used. Accordingly, 5-25 pounds per stump should be used and preferably 10-15 pounds will suffice. Small stumps, however, can be removed using lesser amounts. Because the composition in admixture form may have a heavy consistency, its use can be facilitated by diluting slightly with water. Only enough water should be used to permit the easy application without greatly increasing the amount of solution required to incorporate the necessary quantities of composition in the stump structure.

If admixtures of the selected water-soluble salts are used, the proportions of the respective salts employed

can vary widely. Generally the copper and/or chromium salt will constitute about 15-75%, by weight, of the admixture with the remainder being one or more of the supplementary water-soluble salts hereinbefore mentioned. For example, the compositions tabulated in Table I have been found to have good glow combustion-inducing characteristics.

vention unexpectedly surpassed the nitrate compositions employed in the prior art.

For best results, preparations for burning the stumps are initiated in the later part of the spring of the year, preferably in May. During this period the stumps are cut to ground level, holes bored, and glow combustion inducing composition introduced into the holes. With

Table I

Constituent	Proportions, percent by wt.														
	75	25	50	33 1/3	25	25	25	75	6.25	18.75	56.25	18.75	12.50	56.25	18.75
CuSO ₄ ·5H ₂ O															
FeCl ₃															
CuCl ₂															
Na ₂ Cr ₂ O ₇															
CrO ₃	25	75	50	50	33 1/3	75	25	75							
Pb(C ₂ H ₃ O ₂) ₂									75	75	25	18.75	18.75	12.50	12.50
MnCl ₂															
Na ₂ MoO ₄									33 1/3		25				

To illustrate the instant invention, test composition I having the following formulation was employed.

Chemical:	Weight percent
Cupric chloride	18.75
Sodium dichromate	56.25
Lead acetate	12.50
Manganese chloride	12.50
	100.0

Prior to use the chemicals were mixed in powdered form and thinned with water to the consistency of heavy transmission oil or thick molasses.

In controlled tests a plurality of elm stumps were employed. The stumps were cut substantially flush with the ground. Vertical holes 1-1/2" in diameter on 5"-6" centers were bore 6" deep without penetrating the bottom of the stump. The outside holes were placed 2" from the bark. In addition, holes were bored in the root extensions 3"-4" apart as deep as possible without going all the way through.

Ten pounds of the composition per average stump were employed using about 1/4 pound (1/2 cup of water-thinned mixture) per hole. Each stump was covered with a 4' x 4' tempered hardboard sheeting shield having a sheet of aluminum foil affixed to the underside. One edge of the shield rested on the ground with the opposed edge being held in an elevated position employing a suitable bracing member.

Monthly inspections were made. Any water which had collected in the holes was removed prior to burning. After about four months the stumps were ignited by covering the stump, including the outside edges and root extensions, with kindling. Prior to igniting, the reflector shields were removed but were replaced after the kindling had been reduced to a bed of coals and the stumps began smouldering. One to three weeks were required to burn the stumps.

Under the same controlled field test conditions, sodium nitrate, ammonium nitrate, and test composition II consisting of 50% CuSO₄·5H₂O; 47.5% Na₂Cr₂O₇; 2.5% CrO₃ were employed in a number of stumps.

A panel comprised of forestry experts and members not allied with the forestry profession inspected the results of the field tests and reported their observations. Their conclusions were statistically analyzed and summarized as follows:

Composition:	Percent of stump destroyed
Test Composition I	83
Test Composition II	57
Sodium nitrate	53
Ammonium nitrate	41
Control (no chemical used)	37

It is evident that under the controlled test conditions employed, the efficiency of the compositions of this in-

vention of the composition taking place during the summer, stump burning preferably takes place in late August or early September.

Although elm stumps were employed in the test, it is to be understood that both hardwood and softwood stumps can be substantially destroyed employing the process of this invention. In addition, various modifications in the process set forth in the illustrative embodiment can be made without departing from the scope of this invention. For example, the use of the reflector shield is preferred. Satisfactory results, however, can be obtained without the shield. It is therefore apparent that the subject invention is limited only as defined by the specific claims.

We claim:

1. A method for substantially destroying the subterranean portion of a tree stump which comprises dispersing at least one compound selected from the group consisting of the water-soluble compounds of copper and chromium within said stump in an amount sufficient to promote the glow combustion thereof, and igniting said stump whereby a substantial subterranean portion of said stump is destroyed.
2. A method in accordance with claim 1 in which an admixture of water-soluble compounds of copper and chromium is dispersed within said stump.
3. A method in accordance with claim 2 in which said admixture comprises copper sulfate and a chromium compound selected from the group consisting of the alkali metal chromates and chromic acid.
4. A method for substantially destroying the subterranean portion of a tree stump which comprises dispersing at least one compound selected from the group consisting of the water-soluble compounds of copper and chromium in combination with at least one compound selected from the group consisting of the water-soluble compounds of iron, lead, manganese, and molybdenum within said stump in an amount sufficient to promote the glow combustion thereof, and igniting said stump whereby a substantial subterranean portion of said stump is destroyed.
5. A method in accordance with claim 4 in which an admixture of water-soluble compounds of copper and chromium in combination with at least one compound selected from the group consisting of the water-soluble compounds of iron, lead, manganese, and molybdenum is dispersed within said stump.
6. A method for substantially destroying the subterranean portion of a tree stump which comprises boring a plurality of holes in the stem and root structure of said stump, disposing in said holes a portion of at least one compound selected from the group consisting of the water-soluble compounds of copper and chromium, dispersing an amount of said compound sufficient to promote the glow combustion of said stump therein, and

igniting said stump whereby a substantial subterranean portion of said stump is destroyed.

7. A method in accordance with claim 6 in which an admixture of water-soluble compounds of copper and chromium is dispersed within said stump.

8. A method in accordance with claim 7 in which said admixture comprises copper sulfate and a chromium compound selected from the group consisting of the alkali metal chromates and chromic acid.

9. A method for substantially destroying the subterranean portion of a tree stump which comprises boring a plurality of holes in the stem and root structure of said stump, disposing in said holes a portion of at least one compound selected from the group consisting of the water-soluble compounds of copper and chromium in combination with at least one compound selected from the group consisting of the water-soluble compounds of iron, lead, manganese, and molybdenum, dispersing an amount of said compounds sufficient to promote the glow combustion of said stumps therein, and igniting said stump whereby a substantial subterranean portion of said stump is destroyed.

10. A method in accordance with claim 9 in which an admixture of water-soluble compounds of copper and chromium in combination with at least one compound selected from the group consisting of the water-soluble compounds of iron, lead, manganese, and molybdenum is dispersed within said stump.

11. A method in accordance with claim 10 in which an admixture of water-soluble compounds of copper, chromium, lead, and manganese is dispersed within said stump.

12. A composition for promoting the glow combustion of wood which comprises an admixture of the water-soluble compounds of copper, chromium, lead, and manganese.

13. A composition for promoting the glow combustion of wood which comprises an admixture of copper chloride, alkali metal chromates, lead acetate, and manganese chloride.

14. A composition for promoting the glow combustion of wood having the following formulation:

Component:	Parts by weight
Copper chloride	15-20
5 Alkali metal chromate	50-60
Lead acetate	10-15
Manganese chloride	10-15

15. A composition for promoting the glow combustion of wood having the following formulation:

Component:	Parts by weight
Copper chloride	18.5
Alkali metal chromate	56.5
Lead acetate	12.5
Manganese chloride	12.5
